(57) **CLAIM**

The ornamental design for a tubular cartridge, as shown and described.

DESCRIPTION

This application claims is related to and incorporates by reference U.S. Design Patent application Ser. No. 29/522, 481 filed Mar. 31, 2015, entitled Rail, now U.S. Pat. No. D. 777,814S, which is incorporated herein by reference in its entirety and made a part of this application.

FIG. 1 is a front perspective view showing our tubular cartridge;

FIG. 2 is an enlarged front perspective view thereof;

FIG. 3 is an enlarged front perspective view showing our tubular cartridge with a spouted package, in broken lines, suspended therein;

FIG. 4 is a front end view thereof;

FIG. 5 is an enlarged view of a portion of a component from FIG. 4;

FIG. 6 is an enlarged view of a portion of an alternative embodiment of a component from FIG. 4;

FIG. 7 is an elevation view thereof; and,

FIG. 8 is an enlarged elevation view thereof.

The broken lines showing the spouted package form no part of the claimed design.

The dashed break lines in FIGS. 2, 3 and 8 are shown for clarity of disclosure and indicate enlarged end and side views compared to FIGS. 1 and 7.
